(57) **CLAIM**

The ornamental design for an electronics case, as shown and described.

DESCRIPTION

FIG. 1 is a front perspective view of an electronics case showing the new design;

FIG. 2 is a front elevational view thereof;

FIG. 3 is a rear elevational view thereof;

FIG. 4 is a side elevational view thereof;

FIG. 5 is an opposite side elevational view thereof;

FIG. 6 is a top view thereof;

FIG. 7 is a bottom view thereof;

FIG. 8 is a front elevational view thereof, shown in an open configuration;

FIG. 9 is a top elevational view thereof, shown in an open configuration;

FIG. 10 is a rear perspective view thereof; and,

FIG. 11 is a front perspective view thereof, shown in an open configuration.

The broken lines illustrate portions of the electronics case that form no part of the claimed design.

1 Claim, 11 Drawing Sheets
